UNITED STATES PATENT OFFICE.

EMIL OPDERBECK, OF GELSENKIRCHEN, GERMANY. ASSIGNOR TO HEINRICH KOPPERS,
OF ESSEN-RUHR, GERMANY.

BURNER FOR GAS FURNACES.

Application filed August 24, 1921. Serial No. 494,854.

(GRANTED UNDER THE PROVISIONS OF THE ACT OF MARCH 3, 1921, 41 STAT. L., 1313.)

To all whom it may concern:

Be it known that I, EMIL OPDERBECK, a citizen of Germany, residing at Gelsenkirchen, Germany, have invented certain new and useful Improvements in Burners for Gas Furnaces (for which I have filed an application in Germany, January 30, 1915, Pat. 311282), of which the following is a specification.

10 My invention relates to burners for industrial gas furnaces and more particularly to the furnaces of steam boilers. In furnaces of this kind, the gas pressure is subject to frequent variations. In order to maintain 15 in spite of their variations, the correct ratio of gas and air in the mixture required for a complete and economic combustion, and at the same time to obtain a thorough mixing of gas and air as well as a suitable flow of 20 the combustion gases. I arrange the gas and air passages concentrically and provide a wheel in front of them which is provided with two rims of blades so that a rim is in front of each passage. Motion is imparted 25 to the wheel by the pressure of the heating gas acting on one rim as in a turbine, while the other rim, which is disposed in front of the air passage, acts like a ventilator and thus supplies the air required for combustion. 30 The proportions of the two blade rims are such that, when the number of revolutions is varied, the quantity of air supplied by the ventilator portion of the wheel corresponds to the quantity of gas which 35 actuates the turbine portion of the wheel. To the gas and the air are imparted a rotary motion so that they will be thoroughly mixed immediately at the rear of the burner and are forced against the surface to be 40 heated, for instance the walls of a boiler flue. The result is a uniform and effective combustion and a good transmission of heat.

In the drawings affixed to this specification and forming part thereof, two devices 45 embodying my invention are illustrated diagrammatically by way of example.

In the drawings—

Fig. 1 is an elevation and

Fig. 2 a section of the simplest embodiment of my invention,

50 Figs. 3 and 4 are similar views of a more perfect embodiment.

Referring now to Figs. 1 and 2 the gas

is supplied through a pipe 10, to an annular chamber 11 and leaves the chamber through 55 a rim 12 of guide blades. Here it enters the turbine blade rim 13 of a wheel 14 which revolves in bearings 15 supported by arms 16. The blade rim 17 of wheel 14 which operates as a ventilator draws in air from 60 the interior of casing 11 and forces it into the combustion chamber. The gas and the air are thoroughly mixed in consequence of 65 their rotary motion and the rotating stream of combustible mixture effectively transmits its heat to the heating surface, in the present instance the flue 18 of a boiler 19. The supply of air is regulated by a butterfly valve 20.

Referring now to Figs. 3 and 4, the principal object of this embodiment is ready accessibility, the annular casing 11 being designed in two parts held together by dog clamps 21. Thrust screws 22 in the clamps 21 force the tightening faces 23 and 24 of 70 75 the part 11' of the casing against corresponding faces of the fixed casing 11. After unscrewing screws 22 and removing the bolt 25 by which the clamps 21 are held by means of eyes 26, the entire casing together with 80 the wheel 14 can be turned outside about the hinge 27 so that the interior of the furnace is accessible. The flue 18 is here provided with a refractory lining 28 which, on the one hand, protects the flue and on the 85 other hand, owing to its high temperature, ignites the mixture of gas and air which is particularly important in case of a disturbance in the gas supply. The butterfly valve 20 is here arranged at the rear of bearing 15 90 so that the bearing is readily accessible during operation.

Owing to the inclined position of the gas nozzles a rotary motion is imparted to the gas stream or the flame and the gases are 95 forced against the boiler walls by centrifugal action, so that the efficiency of the boiler is very high. Owing to the rapid rotation of the wheel 14, the entire flue and therefore the process of combustion can readily 100 be observed. If the blades have the correct curvature, any noise, for instance the buzzing sound produced by straight blades, is avoided.

Owing to the simple cleaning of the 105 burner, which is particularly important for

- operation with impure gas, the burner can be cleaned in so short a time that it is only necessary to close the access to the boiler by a separate plate during cleaning, 5 whereupon cleaning can be effected without any disturbance of operation. When such burners are used for the blast heaters in blast furnaces, the arrangement may be such that when the burner is removed by 10 turning it as described, a cover is turned into the casing from the other side so as to close the blast heater. Cleaning can now be effected during the time the previously heated heater is "on blast," that is, the air 15 to be preheated is conducted through it.
- I claim:
1. In a burner for industrial gas furnaces in combination, an air duct and a gas duct, rotary means in the path of the 20 gas traversing said gas duct arranged to be set revolving by the gas and means associated with said rotary means for transmitting the energy of flow of the gas onto the air in said air duct.
  2. In a burner for industrial gas furnaces in combination, an air duct and a gas duct, rotary means in the path of the gas 25 traversing said gas duct arranged to be set revolving by the gas and means associated with said rotary means for exerting a sucking action on the air in said air duct.
  3. In a burner for industrial gas furnaces, in combination, concentric passages for supplying air and gas to the burner, a wheel, 30 a blade rim on said wheel adapted to be rotated by the gas in the manner of a turbine and a blade rim on said wheel adapted to draw in air.
  4. In a burner for industrial gas furnaces, in combination, passages for supplying air and gas to the burner, a wheel, concentric blade rims on said wheel and means 35 for supplying air and gas to said rims.
  5. In a burner for industrial gas furnaces, in combination, passages for supplying air and gas to the burner, and rotary means for imparting a rotary motion to 40 said gas and said air.
  6. In a burner for industrial gas furnaces, in combination, passages for supplying air and gas to the burner, and rotary means for mixing said gas and air and for imparting a rotary motion to said mixture. 45
  7. In a burner for industrial gas furnaces, in combination, passages for supplying air and gas to the burner, a wheel, concentric blade rims on said wheel, an 50 annular chamber, a hollow space surrounded by said annular chamber, means for supply-

ing gas to said wheel through said annular 60 chamber and means for supplying air to said wheel through said hollow space.

8. In a burner for industrial gas furnaces, in combination, passages for supplying air and gas to the burner, a wheel, concentric blade rims on said wheel, an annular chamber, a hollow space surrounded by said annular chamber, means for supplying gas to said wheel through said annular 65 chamber guide blades in said annular chamber.

9. In a burner for industrial gas furnaces, in combination, passages for supplying air and gas to the burner, a wheel, a pair of concentric blade rims on said wheel, 75 an annular chamber, a hollow space surrounded by said annular chamber, means for supplying gas to one of said rims, through said annular chamber, and means for supplying air to the other rim through 80 said hollow space.

10. In a burner for industrial gas furnaces, in combination, passages for supplying air and gas to the burner, a wheel, a pair of concentric blade rims on said wheel, 85 an annular chamber, a hollow space surrounded by said annular chamber, means for supplying gas to one of said rims, through said annular chamber, guide blades 90 in said annular chamber.

11. In a burner for industrial gas furnaces, in combination, passages for supplying air and gas to the burner, a wheel, concentric blade rims on said wheel, and an annular casing adapted to supply gas to 95 said wheel, said casing being made in two parts.

12. In a burner for industrial gas furnaces, in combination, passages for supplying air and gas to the burner, a wheel, concentric blade rims on said wheel, an annular casing adapted to supply gas to said wheel, said casing being made in two parts, and means for turning said burner bodily 100 to the outside.

13. In a burner for industrial gas furnaces, in combination, passages for supplying air and gas to the burner, a wheel, concentric blade rims on said wheel, an annular casing adapted to supply gas to said 110 wheel, said casing being made in two parts and dog clamps and thrust screws in said dog clamps adapted to hold said two parts together.

In testimony whereof I affix my signature.

EMIL OPDERBECK.
